Inventor
O. Shepard

UNITED STATES PATENT OFFICE.

ORLANDO SHEPARD, OF ROCHESTER, OHIO.

IMPROVEMENT IN WATER-ELEVATORS.

Specification forming part of Letters Patent No. **40,125**, dated September 29, 1863.

To all whom it may concern:

Be it known that I, ORLANDO SHEPARD, of Rochester, in the county of Lorain and State of Ohio, have invented new and useful Improvements in Water-Drawers; and I do hereby declare that the following is a full and complete description of the construction and operation of the same, reference being had to the accompanying drawings, making part of this specification, in which—

Figure 1 is a front view, and Fig. 2 a vertical section in the direction of the line *xx* in Fig. 1.

The nature of my invention relates to such an arrangement of parts that the bucket will always be brought up with the same side presented to the spout, insuring thereby the uniform tipping of the same by its ascent.

In the accompanying drawings, A represents a windlass, which is placed across the top of the curb in the usual manner. The windlass is in the form of a double cone joining at the base, but separated by the section B; which is in the form of a straight cylinder, having a length equal to the diameter of the bucket B'. The diameter of the cylinder B is greater than the base of the cone part of the cylinder C C, for the purpose hereinafter specified. At the outer and smaller ends of the cones is a head, D—that is, the cone terminates in the form of a spool—to keep the rope in proper position as it winds upon the cones.

E represents a pulley, about ten inches in diameter, the bearings of which are rigidly attached to the bail of the bucket.

F represents a rope, one end of which is attached to the windlass at F, thence it is passed around the pulley E, and the other or free end

attached to the windlass at F''. The entire length of the rope must of course be sufficient to allow the bucket to reach the water. In consequence of the cone shape of the windlass the rope will wind closely, as seen in Fig. 1; but should the depth of the well require a length of rope sufficient to fill the cones, the greater diameter of the enlarged portion B will turn back the rope upon itself, and thus its relative position will be preserved whether the rope ascends or descends upon the cone.

By means of the cone-shaped windlass the rope will always occupy precisely the same relative positions upon each end of the windlass, as seen in Fig. 1; consequently the ascent of the bucket will be in the center of the curb, and by reason of the diameter of the pulley E the rope is prevented from twisting upon itself, and hence the front side of the bucket is always presented to the spout.

The front side of the bucket is provided with a finger, G, which, in the ascent of the bucket, passes inside of the bail H, attached to the inside of the curb, and as the bucket rises it is thrown forward into the position shown in Fig. 2 and the contents discharged into the spout.

What I claim as my improvement, and desire to secure by Letters Patent, is—

The double cone C C of the windlass with the double rope F F and pulley E, when constructed, arranged, and operating substantially as and for the purpose set forth.

O. SHEPARD.
